FRUIT CONTAINER

Chamlyn K. Sulger, Box 959, and John F. Pandolfo,
23467 Esberg Road, both of Los Altos, Calif. 94022

Filed Dec. 10, 1968, Ser. No. 14,871

Term of patent 3½ years

Int. Cl. D9—04

U.S. Cl. D9—224

FIG. 1 is a top perspective view of a fruit container showing our new design, the lower edge being fragmentarily shown for convenience of illustration;

FIG. 2 is another top perspective view thereof, the lid having been removed for purposes of illustration; and

FIG. 3 is a bottom perspective view of FIG. 2.

We claim:

The ornamental design for a fruit container, substantially as shown and described.
